ATTORNEY.

UNITED STATES PATENT OFFICE.

AMBROSE L. MANAHAN, OF SEATTLE, WASHINGTON.

DESIGN FOR AN EMBLEM.

No. 40,030.

Specification for Design.

Patented June 8, 1909.

Application filed March 8, 1909. Serial No. 482,207. Term of patent 3½ years.

To all whom it may concern:

Be it known that I, AMBROSE L. MANAHAN, a citizen of the United States, residing at Seattle, in the county of King and State of Washington, have invented a certain new, original, and ornamental Design for an Emblem, of which the following is a specification, reference being had to the accompanying drawing, forming a part hereof.

The figure is a face view of an emblem, showing my new design.

I claim:

The ornamental design for an emblem, as shown.

AMBROSE L. MANAHAN.
